UNITED STATES PATENT OFFICE.

ERIC M. SMITH, OF SALTFORD, ENGLAND.

HYDRAULIC PRESS APPARATUS.

Application filed October 31, 1922. Serial No. 598,159.

To all whom it may concern:

Be it known that I, ERIC MONTAGUE SMITH, engineer, a subject of the King of Great Britain, residing at Keynsham Manor, 5 Saltford, in the county of Somerset, England, have invented certain new and useful Improvements in Hydraulic Press Apparatus, of which the following is a specification.

This invention refers to improvements in 10 or relating to hydraulic press apparatus and has for its primary object the provision of an automatically acting self contained hydraulic press, that is to say an apparatus the operative parts of which are all contained 15 within or carried by what is substantially a single casing and the parts of which will all act automatically.

Thus in my improved apparatus the power stroke of the ram is carried to a predetermined limit which is variable at will and there terminated automatically either by mechanical means controlled by the length of stroke or by the attainment of a predetermined pressure. After the end of the power 20 stroke the ram is automatically retracted in readiness for the next power stroke, and so on during the operation of the press.

A further object of the invention is the provision of a variable stroke pump for 25 transferring the pressure liquid to the ram cylinder, the length of the stroke of the pump being automatically varied in accordance with the resistance encountered.

The improved hydraulic press apparatus 30 according to the present invention comprises broadly a ram operating in a cylinder, a reservoir for containing the pressure-liquid formed integral with or directly attached to the ram cylinder, pumping means located 35 within said reservoir to force the pressure-liquid therefrom into the ram cylinder, valve controlled passages inter-connecting the reservoir the cylinder and the pump, automatically acting means capable of variable 40 setting to release the pressure in the ram cylinder and thereby terminate the power stroke of the ram and automatic means for retracting said ram.

Apparatus constructed in accordance with 45 my present invention are illustrated in the accompanying drawings in which:—

Fig. 1 is a vertical sectional view of one

construction of my hydraulic apparatus in which the main ram (after the power stroke) is returned by a jack ram located on 55 the oil reservoir side of the partition between the main ram chamber and the said oil reservoir; while the mechanism for operating the valves, at each end of the travel of the main ram, is shown mounted on the 60 outside of the oil reservoir.

Fig. 2 is a vertical section of a slightly different construction of my hydraulic apparatus, which incorporates a jack ram for the power return stroke, together with a 65 relatively small auxiliary ram (to allow rapid travel of the main ram during the idle part of the power stroke) both of which are shown contained within the main ram itself. Within the oil reservoir are shown twin-opposed pumps and valve-block unit, the automatic reversing mechanism together with its adjustable controlling rod, and the automatic variable pump-stroke mechanism 70 hereinafter described.

Fig. 2^a is a diagram showing the valves and their actions in said apparatus Fig. 2.

Fig. 3 is a vertical sectional view of the upper part of another arrangement of my hydraulic apparatus wherein all the parts 80 are automatically caused to function; and this arrangement may conveniently be termed the "full automatic" apparatus, in so far that it is arranged to reverse automatically either at a predetermined length of 85 stroke or at a predetermined total pressure of the ram.

Fig. 4 is a vertical sectional view at right angles to Fig. 6.

Fig. 5 is a plan view of Figs. 6 and 7, with 90 the top cover removed.

Fig. 6 is a vertical sectional view on a reduced scale of the lower part of the apparatus shown in Figs. 6 to 8, in which a spring for returning the main ram (after each 95 power stroke) is located and arranged to operate within the main ram itself.

Fig. 7 is a separate view of the variable gear (hereinbefore referred to for operating the oil pump) for automatically varying the length or extent of the pump stroke without requiring any variation either (a) of the speed of the shaft or (b) of the power 100 (derived from any suitable source) applied

to said shaft by which said pump is operated.

Fig. 8 is an end view (in elevation) on line 11—11 Fig. 7 looking in the direction of the arrow α .

Fig. 9 is a similar view to Fig. 6, but with the eccentric sleeve part of the said gear rotated into a different position relatively to the other parts of said gear.

10 Referring now more particularly to Fig. 1:—

A is the main ram chamber. B the main ram, C the oil reservoir. D is the jack ram.

In this apparatus (Fig. 1) the main casting E has the partition E^1 formed integral therewith (by casting or otherwise) and also the jack ram cylinder E^2 .

15 The part of the main casing E enclosing the oil reservoir C in this arrangement is formed integral with the part forming the main ram cylinder A.

20 E^3 is removable cover fixed to the top, and E^4 removable cover fixed to the bottom, of the said main casing E.

25 E^5 E^6 are downwardly extending pins rigidly fixed to the underside of the partition E^1 and fitting in corresponding holes in the ram B to prevent any axial rotation of the latter relative to the casing E.

30 B¹ is stout rod attached to the top of the main ram B and adapted to slide through the gland E⁵ in the partition E¹ and above the latter the jack ram D is attached to said rod B¹.

35 This rod B¹ also has rigidly affixed thereto the laterally extending arm B² and the vertical rod B³, or if desired the vertical rod B³ may slidably pass through the partition E¹ and be rigidly fixed direct to the main ram B.

40 D² is an oil outlet passage in the jack ram D controlled by the valve D³ which acts as a safety valve to prevent excessive retraction of the main ram, by coming into contact with the abutment D⁴ fixed in the cover E³ and being forced open to thereby release the pressure in the jack ram cylinder D¹.

45 F is spring controlled slotted quadrant (i. e. slotted at F¹) of automatically acting valve trip gear; which quadrant is pivoted at F² on the fixed mount E⁷ on the top cover E⁸ and is provided with the downwardly extending rigid arm F³ which I will term the striker arm F³.

50 F⁴ is a stirrup (provided with a roller) adapted to travel freely along the curved slot F¹.

55 F⁵ is a stout spring attached at one end to said stirrup F⁴ and at its other end fixedly attached to a lug or anchorage F⁶ on the cover E⁸; this point of anchorage F⁶ being in the vertical plane of the axis F² about which the striker arm F³ oscillates.

60 B⁴ and B⁵ are two short rigid arms or devices adjustably mounted on the rod or post

B⁸ and extending laterally therefrom so as to be adapted to alternately act on the crank pin F⁷ fixed on the shaft F² of the quadrant F to thereby partially rotate the latter around its axis F², whereby the strong 70 spring F⁸ is put under tension until the stirrup F⁴ has passed the dead centre and can race down the slot F¹ whereupon the quadrant is tilted over with a jerk or snap and with it the striker arm F³; and thus the 75 striker arm F³ is caused to oscillate back and forth with the desired "snap action" in each direction alternately.

80 G is slide bar carrying two stout upright arms or posts G¹ and G², which latter are located in the path of travel of the lower end of the striker arm F³. This slide bar G is held freely slidable in the guides or bearings G³ and G⁴ and towards its right hand end this slide bar G is provided with the cam surface G⁵ to act on (depress) one or other of the two valve rods H¹ and H² alternately against the action of springs arranged to return said valves and rods.

85 H is an oil pump; H³ are eccentrics on the shaft H⁴ (driven from any suitable source of power) to drive the plungers of the oil pumps H H.

90 H⁵ is an independent valve operating rod adapted to be actuated by hand to open 95 communication through a passage not appearing in the sectional view Figure 1 between the main ram chamber A and the oil reservoir C, and thus enable the power stroke of the main ram to be stopped (by hand) if desired at any required point in 100 said stroke.

95 H⁶ is the elongated stem of the valve H⁷ 105 controlling the oil passage through the partition E¹ between the main ram chamber A and the oil reservoir C. The valve stem H⁶ is automatically operated by the rigid arm B² at the limit of the power stroke of the main ram B to thus automatically stop the power stroke if the main automatically-acting mechanism, G, H¹, H² etc., F etc., should 110 from any cause fail to function properly.

115 Any oil that may escape past the main ram B will be forced, by the underside of the latter, past the non-return valve H⁸ and delivered through the conduit H⁹ back into the oil reservoir C.

H¹⁰ is a safety valve in the pump circuit.

120 The operation of this apparatus (Fig. 1) is as follows:—

125 The pump H is actuated and forces oil (through passages not appearing in the sectional view Figure 1) from the oil reservoir C into the main ram chamber A and into the jack ram cylinder D¹ of the jack ram D during the power stroke, at the end of which latter the rod B³ actuates the valve trip gear F, F³, F⁴, F⁵, G, G¹, G², G⁵, H¹, H², and thereupon the jack ram D (to which the pump continuously delivers oil under pres- 130

sure) imparts the return stroke to the main ram B and the latter forces the oil in the main ram chamber back into the oil reservoir C through the now open communication between the chambers A and C until, at the end of the return stroke of the main ram B, the valve trip gear aforesaid is actuated in the reverse direction whereupon the pump H again delivers oil under pressure to the main ram cylinder A; and the cycle is repeated, and so on.

Or if desired the pump H can be arranged to only deliver oil under pressure to the jack ram for the return stroke of the main ram and not during the power stroke of the latter.

Referring now more particularly to Figs. 2 and 2^a.

The parts of the valve trip gear F, F¹, G, G¹, G², etc., are arranged inside the oil reservoir C, and are actuated by the rod B³ attached to the main ram B and in this arrangement the quadrant F has rigidly fixed thereto the crank arm F⁶ the outer end of which latter is acted on alternately by the devices B⁴ and B⁵ adjustably fixed on the rod B³ to thereby operate said trip gear.

In this arrangement, the part E^x of the main casing which encloses the oil reservoir chamber C is shown formed separately from the main casing E in which latter is formed the main ram cylinder A for the main ram B; the said two casings or parts E E^x being secured to each other in any suitable manner. Or said main casing E E^x may if desired be formed integral, for example as in Fig. 1.

In this apparatus (Fig. 2) the main ram B is itself formed hollow, i. e. so as to form the jack ram cylinder D⁶ and the auxiliary ram D⁶ within the main ram B.

To the partition E¹ is rigidly affixed, coaxial with the main ram cylinder A, the downwardly extending post or rod I, the cross sectional area of which is less than the interior bore (forming the jack ram cylinder D⁶) of the main ram B through the top of which latter said rod I makes a close slidable fit (e. g. through any suitable gland or packing in the top end of said main ram B) while the lower end I¹ of this post or rod I is formed like a double acting hydraulic piston; only in this case this head end I¹ is, of course, stationary and its cylinder (the main ram B) is reciprocated with respect to said head end or piston I¹.

In order to explain the action of this press I will now describe it with reference to Fig. 2^a. I² is an oil conduit through rod I leading from the oil pump conduit I^x to the auxiliary ram cylinder D⁶ below the head I¹, I³ is an oil conduit leading from the pump conduit I^x to the jack ram cylinder D⁶ above the head I¹ (this chamber D⁶ is always open to the pump pressure while the press is work-

ing). I⁴ is a conduit from the oil reservoir C to the main ram cylinder A which is controlled by a flooding valve I⁵ and this valve I⁵ allows oil to be drawn into the main ram cylinder A during the idle part of the power stroke of ram B. I⁶ is a lightly spring-loaded valve which prevents oil under pressure from entering main ram cylinder A until the main ram B encounters greater resistance than can be overcome by auxiliary ram D⁶. I⁷ is an automatic exhaust non-return valve from chamber A to reservoir C. I⁸ and I⁹ are respectively exhaust and in-let valves operated by the automatic valve operating gear F, F¹, F², G, G¹, G², etc., (Fig. 2). I¹⁰ is the valve controlling supply of oil from the pump to the jack ram D⁶. I¹¹ is a safety valve in the pump circuit which blows when the maximum working pressure is reached.

H⁸ is non-return valve; and H⁹ conduit through which any oil, which may escape past the exterior of the main ram B, is forced by the latter back into the oil reservoir chamber C. Automatically acting stroke limiting valves (such as H⁸ H⁷ in Fig. 1) may be fitted; and also, if desired, a hand operated mechanism (such as the rod H⁵ Fig. 1) for manually stopping the power stroke of the main ram B at any desired point in said stroke.

The method of operation of the apparatus (Figs. 2 and 2^a) is as follows:—

The ram B is about to commence the power stroke, the pumps to deliver oil to the auxiliary cylinder D⁶ and jack-ram cylinder D⁶; hence as main ram B descends it draws oil from reservoir C into main ram cylinder A through valve I⁵. When ram B reaches its work the pressure from the pumps increases and opens valve I⁶, valve I⁶ then automatically closes and the oil under pressure from the pumps is delivered to the main ram cylinder A as well as auxiliary ram D⁶ and the ram B continues to travel at full pressure. When the predetermined stroke has been completed the automatic valve gear, previously mentioned, closes valve I⁹, opens exhaust valve I⁸, and the automatic exhaust valve I⁷ opens. The jack ram cylinder D⁶ is still open to the full pressure from the pumps, hence ram B is returned to its original position and the oil from cylinders A and D⁶ is returned to reservoir C through conduits I², I¹², and I¹³.

Referring now to the apparatus shown in Figs. 3 to 6:—

In this arrangement the oil pump plunger Z¹ (Fig. 4) is operated by one or other of the three eccentrics L¹ or L² or L³ fixed on the driving shaft L which latter is capable of being moved endwise so as to bring either one or other said eccentrics into position to operate said plunger and to be held in said position by bringing one or other

of the circular grooves L^4 or L^5 or L^6 under the pivoted plate or pawl L^7 (Fig. 5) so that the latter can rest in said groove and thereby prevent endwise movement of the shaft L during rotation.

Z^2 are springs which through the medium of the cross head Z^8 (Fig. 4) fixed to the plunger Z^1 keep the anti-friction roller Z^4 (mounted on the outer end of said plunger Z^1) pressed against the eccentric operating the said plunger e. g. against the eccentric L^2 as in Figs. 4 and 5.

The oil under pressure from said pump is delivered into the main ram cylinder A for example through a conduit Z^5 as indicated in dotted lines in Fig. 3; which conduit is in open connection with the conduit Z^6 , see Fig. 3.

This conduit Z^6 leads into the passage M but is normally held closed by the valve M^1 which is forced down on its seating by the pin M^2 which latter is forced down by the projection N^1 on the lever N pivoted at N^2 at one end, while the other end of this lever N is held down by the adjustable spring N^3 , and the tension on this spring N^3 can be increased or diminished by revolving the nut or collar N^4 on the screwed rod N^5 which latter is attached to said lever N ; so that the valve M^1 can thus be set to lift at any predetermined pressure of the oil in the cylinder A and conduits Z^5 Z^6 .

When the predetermined pressure to which the valve M^1 has been set is exceeded and the valve M^1 lifts, thereupon the oil under pressure passes through the passage M and forces outwardly the plunger M^3 —the extension of which M^4 forces (to the left) the lever M^5 rigidly fixed on the rocker shaft M^6 —see Figs. 3 and 5.

On this rocker shaft M^6 there is also rigidly fixed the lever or trigger M^7 notched at M^8 (see Fig. 3) and normally kept pressed to the right by the spring M^9 fixed on the back of said trigger M^7 and bearing against the inside of the casing E^x of the oil chamber C .

O is a lever pivoted at O^x in a fixed mount; the end O^1 of this lever normally resting upon and being supported by the notch M^8 of the trigger or lever member M^7 ; while the other end O^2 of said lever (when the end O^1 is supported on the notch M^8) forces down, and keeps forced down, the valve O^3 upon its seating so as to close the outlet O^4 leading from the cylinder A into the oil chamber C .

Through a lateral projection or lug O^5 (Fig. 4) on the side of this lever O an adjustable screw pin O^6 is mounted and adjusted to such position that when the end O^1 of the lever O descends (upon withdrawal of the notch M^8) thereupon the pin O^6 forces down the valve M^{10} and thereby releases the pressure of the oil in the con-

duit M and cylinder M^{11} thus allowing the spring M^{12} to return the plunger M^8 to its original position.

O^7 (Fig. 4) is upwardly extending rigid rod fixed to the lever O , with the adjustable collar O^8 thereon.

B^3 (Figs. 4 and 5) is vertical rod rigidly attached at its lower end to the main ram B (see Fig. 6) and towards its upper end this rod is provided with the adjustable collar O^9 thereon; the collar O^8 on the rod O^7 being in the upward path of travel of the collar O^9 .

The operation is as follows:—

At the end of the return stroke and at the commencement of the power stroke of the main ram B the parts are in the position shown in Fig. 3. As the power stroke of the main ram B proceeds and eventually the predetermined pressure (to which the valve M^1 has been set—by the collar N^4) is reached, and the valve M^1 is forced open by said pressure, thereupon the plunger M^3 and extension M^4 force the lever M^5 and with it the trigger or lever member M^7 to the left until the end O^1 of the lever O is released (by the notch M^8) and descends, and the other end O^2 slightly ascends and allows the valve O^3 to open and thereby release the oil pressure in the cylinder A ; whereupon the return stroke is imparted to the main ram B by the spring B^8 (see Fig. 6) which in this case is located in the hollow part of the main ram B and is compressed therein against the fixed head B^9 on the fixed rod B^{10} carried on the partition E^1 of the casing E .

As the main ram arrives at the end of the return stroke, the rod B^3 forces the collar O^9 against the collar O^8 on the rod O^7 and the latter lifts the end O^1 of the lever O until the notch M^8 of the trigger M^7 is forced by the spring M^9 under said end O^1 of the lever O , and thereby the valve O^3 is again securely locked and held in the closed position, in readiness for the next power stroke which then commences; and so on.

Hence it will be seen that the press can be set so that any desired pressure can be exerted on the main ram and on such predetermined pressure being reached or exceeded, thereupon the pressure is automatically released and the ram automatically returned, and the parts reset automatically, and the next power stroke commenced automatically and so on.

P (see Figs. 3 and 5) is a cam shaft adapted to be manually operated from the exterior of the casing E^x for example by a hand lever P^1 as shown in Fig. 5.

P^2 and P^3 (see Figs. 3 and 5) are two cams fixedly mounted on said cam shaft P ; the cam P^2 is adapted to act on the lever M^5 to thereby force the trigger M^7 to re-

lease the end O^1 of the lever O (by hand) while the cam P^3 will act on the under side of the lever O towards the end O^1 thereof to raise the latter (by hand) when required.

- If it is desired to operate this press as shown in Figs. 3 to 6 with reference to stroke and not pressure:—

First of all lock the valve M^1 by screwing the nut or collar N^4 to its limit. This will prevent the aforementioned pressure-release from operating. The press can now be controlled with regard to the ram stroke as follows:—

The main ram B has traversed to the pre-determined length of its power stroke, the rod B^8 which is rigidly connected to said ram B has brought the collar O^9 down in contact with the lever M^{18} which is rigidly fixed to the shaft M^6 , thus releasing end O^1 of lever O from notch M^8 , hence the main exhaust valve O^3 opens as previously described. The oil in cylinder A then exhausts to reservoir C through conduit O^4 , and the main ram B is returned to its initial position by the spring B^8 (Fig. 6). At the end of this return traverse the collar O^9 comes in contact with collar O^8 which in turn by means of rod O^7 pulls lever O upwards until the end O^1 engages with the notch M^8 in the spring loaded lever M^7 ; the main exhaust valve O^3 is then closed and the press then starts on the next power stroke and so on.

It will thus be seen that the operation of this form of hydraulic apparatus is fully automatic in every sense.

Referring now to Figs. 7 to 9, which show a special form of variable gear for operating the oil pump in my aforesaid hydraulic apparatus; this variable gear is as follows:—

Q is shaft for operating the pump through the medium of said variable gear; this shaft Q being arranged to be rotated at a constant speed and at a constant power derived from any suitable source of power or by hand operated means. This shaft Q is supported in the upright post R^1 of the fixed frame R and in the axially adjustable bearing R^2 in the upright part R^3 of said fixed frame or support R ; and shaft Q is incapable of endwise movement. The adjustable bearing R^2 is provided with a recess R^4 adapted to receive therein one end of the spring S the other end of which latter bears in an annular recess T^x in the end of the stout slidable sleeve or bush T which latter is splined on said shaft Q so as to be slidable endwise on said shaft. R^5 is a stop ring or stop plate (through which the power shaft Q passes freely) which is arranged and mounted in juxtaposition to the right hand end of the slidable bush T and supported in the upright R^3 of the fixed frame through the medium of the screwed

pins R^6 which pass freely through said vertical support R^3 and each having the screwed nut R^7 thereon (see Fig. 7) so that by correspondingly screwing said nuts R^7 along said screw pins R^6 in one direction or the other thereby the stop plate R^5 can be adjusted toward or away from the slidable sleeve or bush T and thus form a fixed abutment at any desired point to limit the movement to the right of the slidable sleeve or bush T .

By adjusting the bearing R^2 towards or away from said bush T thereby the spring S is more or less compressed between said bearing R^2 and bush T ; and thus offers greater or less initial resistance to the endwise movement of the bush T .

The external periphery of this slidable bush T is eccentric with the bore thereof i. e. eccentric with the shaft Q upon which latter same can slide axially along the feather Q^1 .

The said external periphery of the bush T is provided with a helical groove or female thread T^1 .

On the exterior of this slidable bush T an eccentric ring U is mounted which ring is provided interiorly with a male thread U^1 adapted to fit in the aforesaid helical groove or female thread T^1 in the bush T .

This ring U is provided with the external flange U^2 so as to hold in position on said ring U the sleeve or strap W which latter has the rod or rigid arm W^1 rigidly attached thereto.

The sleeve or strap W is held in position on said ring U by the aforesaid annular flange U^2 and by means of the locking ring U^3 screwed on to said ring U . This rigid rod W^1 passes through the cross head or short shaft X (in which it is a sliding fit) the latter having trunnions or ends X^1 journalled in the bearings X^2 formed in the fixed frame R ; and this rigid rod W^1 below said bearing is thus caused to oscillate more or less and thereby to operate the pump—for example as indicated in dotted lines in Fig. 2 of the drawings.

The operation of this variable gear is as follows:

Upon the shaft Q being rotated the stout rigid rod W^1 for operating the pump is oscillated for the maximum distance and consequently the maximum stroke is imparted to the pump.

As the pressure of the oil increases, i. e. as the resistance of the pump to its operation increases, thereby resistance to the rotation of the slidable bush T by the shaft Q increases and this resistance tends to cause said slidable bush T to slightly rotate (on the helical groove T^1 and male thread U^1) relatively to the ring U and, as the latter is held against any axial displacement, therefore the bush T will slide (along the shaft

- Q) towards the fixed abutment R⁵ and further compress the spring S in so doing, and at the same time the relative positions of the eccentrics T and U will be changed, 5 and thus reduce the extent of the oscillation of the pump operating rod W¹ and thereby automatically increase the power; and, as further resistance is offered by the pump, thereby the slidable bush T will be 10 caused to be moved further towards the fixed abutment R⁵, until finally, if the resistance of the pump continues to increase, the two eccentrics T and U will be moved into such position relatively to one another 15 that no movement will be imparted thereby to the pump, and the operation of the pump will thereupon cease.

By adjusting the bearing ring R², thereby the variable gear can be arranged to stop 20 further pumping as soon as any predetermined pressure of the oil by said pump has been attained.

This variable gear is shown applied in only one of the several alternative forms of 25 apparatus illustrated in the accompanying drawings viz in Fig. 2 as aforesaid; but said variable gear may be applied for operating the pumps in any of the other forms of my apparatus as desired.

30 Hydraulic apparatus according to my present invention has (inter alia) the following advantages:—

1. Self-contained, and hence portable.
2. No external piping.
3. No external working joint or gland under pressure.
4. Automatic control of ram stroke in each direction.
5. Ram stroke automatically variable in 40 relation to total ram stroke.
6. Automatic varying pump strokes.
  - (a) which allows maximum load to be predetermined at which ram will work.
  - (b) which allows ram to work with maximum efficiency up to maximum load at constant horse power.
  - (c) which controls the speed of ram travel.
  - (d) enables a large press to be worked 50 by very small power from any suitable source; or by hand power if necessary.
7. Automatic valve trip mechanism.
  - (a) Mechanically operated.
  - (b) Hydraulically operated.
- 55 Either of which two last-named mechanism can be instantly stopped by hand.
8. Main ram with integral jack ram for power reversal.
9. Main ram with an auxiliary ram and 60 an inverted jack ram within itself for high speed traverse at low total pressure, and power reversal.
10. Since whole unit is self-contained only a small quantity of liquid is used which 65 circulates continually within the apparatus

and hence this liquid can be of high quality to preserve leathers and prevent corrosion and can be filtered so that no foreign matter can injure the valves or other working parts.

70 A self-contained hydraulic apparatus or hydraulic unit according to this invention may be employed for various purposes such for example as the following:—

Punching, shearing and riveting machines; bar cropping (for ferro-concrete work, etc.); structural section cropping; hot pressing (instead of drop forging); piercing and pressing purpose; bending and straightening machines; serrating corrugated iron sheets; notching structural sections; hydraulic loading on rolling mills, etc.; briquette making presses; brick making and pottery moulding machines; foundry moulding; die casting; independent control of naval guns, etc.; hollow-ware pressing in multiple; silver trade pressing; embossing; medal striking, piercing, etc.; fibre and paper compressing machines; baling (jute, tobacco, hay, cotton, etc.; pressing machines); application to tensile and compression testing machines; quartz and ore crushing; extract drug and cereal compressing; nib making in multiple; hydraulic arbor press; book binding, etc. etc.; or for 95 any other machines or purposes to which same may be applicable.

90 What I claim is:—

1. A self contained hydraulic press apparatus comprising a ram operating in a cylinder, a reservoir for containing the pressure-liquid attached to the ram cylinder, pumping means located within the reservoir to force the pressure-liquid therefrom into the ram cylinder, valve controlled passages 100 inter-connecting the reservoir the cylinder and the pumping means, automatically acting means capable of variable setting to release the pressure in the cylinder and thereby terminate the power stroke of the ram, and automatic means for retracting said ram.

105 2. A self contained hydraulic press apparatus comprising a ram operating in a cylinder, a pressure-liquid reservoir directly attached to the ram cylinder, a pump within the reservoir to transfer the pressure-liquid therefrom to the cylinder to actuate the ram, valve controlled passages inter-connecting the reservoir the cylinder and the pump, a 110 rod attached to the ram and extending into the reservoir and therein provided with an abutment adjustable thereon to engage, at any predetermined point in the travel of said rod, a valve releasing device to open communication between the cylinder and the reservoir for return of the pressure-liquid, and automatic means for retracting the ram,

115 3. A self contained hydraulic press apparatus comprising a ram operating in a cylinder 120

der, a reservoir for the pressure-liquid directly attached to the cylinder, a pump within said reservoir to force the pressure-liquid to the ram cylinder, valve controlled passages inter-connecting the reservoir the cylinder and the pump, a rod attached to the ram and extending through the division wall into the reservoir and carrying therein variable means to actuate, at any predetermined point in the power stroke of the ram a valve to open communication between the reservoir and the cylinder to stop the power stroke of the ram and permit return of the pressure-liquid, and variable means for releasing the pressure-liquid in the cylinder upon the attainment of any predetermined pressure therein.

4. A self contained hydraulic press apparatus comprising a ram operating in a cylinder, a reservoir for the pressure-liquid directly attached to the cylinder, a pump within said reservoir to force the pressure-liquid to the ram cylinder, valve controlled passages inter-connecting the reservoir the cylinder and the pump, a rod attached to the ram and extending through the division wall into the reservoir and carrying therein variable means to actuate, at any predetermined point in the power stroke of the ram, a valve to open communication between the reservoir and the cylinder to stop the power stroke of the ram and permit return of the pressure-liquid, and a variable tension spring loaded system of levers and trip gear operating upon the attainment of a predetermined pressure in the ram cylinder to release the pressure-liquid in the ram cylinder thereby terminating the power stroke of the ram and permitting the return of the pressure-liquid to the reservoir.

5. A self contained hydraulic press apparatus comprising a ram operating in a cylinder, a reservoir for the pressure-liquid directly attached to the cylinder, a pump within said reservoir to force the pressure-liquid to the ram cylinder, valve controlled passages inter-connecting the reservoir the cylinder and the pump, a rod attached to the ram and extending through the division wall into the reservoir and carrying therein variable means to actuate, at any predetermined point in the power stroke of the ram, a valve to open communication between the reservoir and the cylinder to stop the power stroke of the ram and permit return of the pressure-liquid, and a variable tension spring loaded system of levers and trip gear operating upon the attainment of a predetermined pressure in the ram cylinder to release the pressure-liquid in the ram cylinder thereby terminating the power stroke of the ram and permitting the return of the pressure-liquid to the reservoir, means for automatically retracting the ram after each power stroke and for commencing the next power stroke.
